UNITED STATES PATENT OFFICE.

FREDERICK W. EHRLICH, OF NEWARK, NEW JERSEY.

DESIGN FOR AN AUTOMOBILE RADIATOR ORNAMENT.

Application filed October 4, 1926. Serial No. 19,237. Term of patent 7 years.

To all whom it may concern:

Be it known that I, FREDERICK W. EHRLICH, a citizen of the United States, residing at Newark, in the county of Essex and State of New Jersey, have invented a new, original, and ornamental Design for Automobile Radiator Ornaments, of which the following is a specification, reference being had to the accompanying drawing, forming part thereof.

In said drawing, Figure 1 is an elevation showing one side, Figure 2 is an elevation showing the opposite side, and Figure 3 is a front elevation of an automobile radiator ornament, showing my new design.

I claim:

The ornamental design for automobile radiator ornament, as shown.

Dated this 31st day of August, 1926.

FREDERICK W. EHRLICH.
